The ornamental design for scissors handles, as shown and described.

DESCRIPTION

FIG. 1 is a right front top perspective view of the scissors handles;

FIG. 2 is a top view thereof;

FIG. 3 is a right side view thereof;

FIG. 4 is a left side view thereof;

FIG. 5 is a rera view thereof;

FIG. 6 is a front view thereof;

FIG. 7 is a bottom view thereof; and,

FIG. 8 is a top view thereof in the open position.

The broken line showings throughout the views of scissor blades are for illustrative purposes only and form no part of the claimed design.

UNITED STATES PATENT AND TRADEMARK OFFICE
CERTIFICATE OF CORRECTION

PATENT NO. : Des. 406,739
DATED : March 16, 1998
INVENTOR(S) : Tarozzi

It is certified that error appears in the above-identified patent and that said Letters Patent is hereby corrected as shown below:

“FIG. 5 is a rera” should be “FIG. 5 is a rear”

Signed and Sealed this
Fifteenth Day of June, 1999

Attest:

Q. TODD DICKINSON

Attesting Officer

Acting Commissioner of Patents and Trademarks
